HEAT EXCHANGE APPARATUS FOR COOLING LIQUIDS

Frank M. Bennett, Canton, Ohio

Application June 2, 1954, Serial No. 433,877

6 Claims. (Cl. 62—141)

The invention relates to apparatus for cooling liquids, and more particularly to a cooler for water for use in air conditioning apparatus and the like.

An object of the invention is to provide water cooling apparatus of simple and inexpensive construction.

Another object is to provide such apparatus which maintains such water and refrigerant velocities as are required to affect a maximum rate of heat transmission from the water to the refrigerant.

A further object is to provide water cooling apparatus which occupies a minimum space.

A still further object is to provide such cooling apparatus which will not be damaged by accidental freezing of the water being cooled.

Another object of the invention is to provide a heat exchange apparatus for cooling water, in which the refrigerant coil is located within a coiled tube through which the water is passed in a thin film surrounding the refrigerant coil.

A further object is to provide such apparatus in which the coiled tube through which the water passes is formed of a plastic material which is sufficiently elastic to permit freezing of water therein without rupturing the tube.

A still further object is to provide apparatus of this character comprising a container, a water header at the top of the container and connected to a water supply, a refrigerant coil within the container, one end of the coil being connected, through an expansion valve, to a compressor or condenser, the other end of the coil returning to the compressor or condenser, a water coil surrounding the refrigerant coil and having one end connected to the water header and the other end opening into the container, and an outlet for cooled water communicating with the container.

The above objects together with others which will be apparent from the drawings and following description, or which may be later referred to, may be attained by constructing the improved heat exchange apparatus in the manner hereinafter described in detail and illustrated in the accompanying drawings in which:

Fig. 1 is a vertical, sectional view of a water cooling apparatus embodying the invention;

Fig. 2 a transverse, sectional view, taken on the line 2—2, Fig. 1;

Fig. 3 a transverse, sectional view, taken on the line 3—3, Fig. 1; and

Fig. 4 a fragmentary sectional view of one end of one of the refrigerant tubes and the surrounding water tube.

The heat exchange apparatus is located within an inner shell 10 having a water distributing chamber 11 connected to one end thereof, which may be the upper end as shown in Fig. 1. This inner shell is of water-tight construction and may be of cylindrical shape as shown.

An outer shell 12 is spaced from, and entirely surrounds, the inner shell 10 and distributing chamber 11, and the space therebetween is filled with suitable heat and cold insulation such as cork or the like, as indicated at 13.

A water inlet 14 is provided in the water distributing

2

chamber 11, and connected to any suitable water supply for constantly furnishing water to the distributing chamber.

Refrigerant is conveyed from a compressor or condenser through the pipe 15 through a control valve 16, which may be a thermostatic expansion valve or constant pressure expansion valve of conventional type, or a metering tube commonly known as a capillary tube, to the refrigerant distributor 17 extending into the inner shell 10, or in the case of the metering tube, directly to the ends 21 of the coils 18, through the distributing tubes 22.

One or more cooling tubes, preferably in the form of helical coils, are located within the inner shell 10. In Fig. 1 three such tubes are shown, indicated at 18, being formed into helical coils and located one above the other within the shell 10.

Where a multiple cooling coil unit is provided, as shown in the drawings, the upper ends of the several tubes 18 are located through the water distributing chamber 11 and communicate with a header 19. The outlet of said header is connected to a return pipe 20 through which the evaporated refrigerant is returned to the compressor or condenser of the refrigerating unit.

The other end of each coil 18 is closed, as shown at 21, and the refrigerant distributing tubes 22 connect these closed ends of the cooling coils to the refrigerant distributor 17, or to the metering tube.

The upper end portions of the cooling tubes 18 are located through the outlet nipples 23 in the lower wall 24 of the water distributing chamber 11. These nipples are of slightly larger inside diameter than the outside diameter of the cooling tubes 18, so as to permit water to be discharged from the water distributing chamber into the shell 10, the water passing in a thin sheet between the cooling tube 18 and the surrounding nipple 23.

For the purpose of rapidly cooling the water as it is discharged from the water distributing chamber, tubes 25 surround the cooling tubes 18. The tubes 25 are open at both ends, the upper end of each tube 25 being connected to the corresponding outlet nipple 23 and the other end thereof terminating at the closed end 21 of the corresponding cooling tube 18, as indicated at 26 in Fig. 4.

Each water tube 25 is of such diameter relative to the corresponding cooling tube 18, that it forms an annular water passage 27, between the tubes 18 and 25, of such area as to cause the water velocity required for the maximum practical rate of heat transfer from the water in the tube 25 to the refrigerant in tube 18.

The water tubes 25 are formed of an elastic plastic material having sufficient elasticity to prevent rupture thereof in the event that the water should freeze therein.

A water outlet 28 is provided at the upper end of the shell 10, and may be connected to an air conditioning system or other device when cold water is required.

In the operation of the apparatus, refrigerant from a refrigerating unit is conveyed through the pipe 15 to the control valve 16, and thence through the refrigerant distributor 17 and distributing tubes 22 to the ends 21 of the cooling tubes 18, the refrigerant passing upwardly through these cooling tubes. The evaporated refrigerant enters the header 19 and is returned through outlet pipe 20 to the refrigerating unit.

Water to be cooled enters the water distributing chamber 11 through the inlet 14 and is continuously discharged from the distributing chamber through the outlet nipples 23 into the elastic water tubes 25.

The water passes through each water tube 25 in a thin annular sheet surrounding the cooling tube 18, causing a rapid rate of heat transfer from the water in the tube 25 to the refrigerant in the tube 18.

After passing through the tubes 25, the cooled water

is discharged from the open ends 26 of the tubes into the shell 10, and passes out of the shell, through the outlet 28, to the air conditioning system or other apparatus in which cold water is required.

Although three cooling coils are shown in the drawings, it should be understood that this is only for the purpose of illustration, as one or more coils may be located within the shell as may be required for any particular case.

It should also be understood that a plurality of units such as shown in the drawings may be connected to a common water supply and outlet line and to a common refrigeration unit without in any manner changing the construction as illustrated and described.

In the foregoing description, certain terms have been used for brevity, clearness and understanding, but no unnecessary limitations are to be implied therefrom beyond the requirements of the prior art, because such words are used for descriptive purposes herein and are intended to be broadly construed.

Moreover, the embodiments of the improved construction illustrated and described herein are by way of example, and the scope of the present invention is not limited to the exact details of construction.

Having now described the invention or discovery, the construction, the operation, and use of preferred embodiments thereof, and the advantageous new and useful results obtained thereby; the new and useful construction, and reasonable mechanical equivalents thereof obvious to those skilled in the art, are set forth in the appended claims.

I claim:

1. A liquid cooler comprising a shell, a water distributing chamber mounted upon the top of the shell, means for supplying water to said distributing chamber, a cooling coil in the shell, the upper end of the coil being located through the distributing chamber, an evaporated refrigerant return line connected to said upper end of the coil, means for supplying refrigerant to the lower end of the coil, an outlet nipple on the distributing chamber surrounding said upper end of the cooling coil, a water tube surrounding said cooling coil within the shell, the upper end of the water tube being connected to said nipple, the lower end of the water tube opening within the shell, and a cold water outlet in the shell and located through said water distributing chamber.

2. A liquid cooler comprising a shell, a water distributing chamber mounted upon the top of the shell, means for supplying water to said distributing chamber, a cooling coil in the shell, the upper end of the coil being located through the distributing chamber, an evaporated refrigerant return line connected to said upper end of the coil, means for supplying refrigerant to the lower end of the coil, an outlet nipple on the distributing chamber surrounding said upper end of the cooling coil, an elastic water tube surrounding said cooling coil within the shell, the upper end of the water tube being connected to said nipple, the lower end of the water tube opening within the shell, and a cold water outlet in the shell and located through said water distributing chamber.

3. A liquid cooler comprising a shell, a water distributing chamber mounted upon the top of the shell, means for supplying water to said distributing chamber, a cooling coil in the shell, the upper end of the coil being located through the distributing chamber, an evaporated

refrigerant return line connected to said upper end of the coil, a control valve, a refrigerant supply line connected to said valve, a refrigerant distributor tube connecting the valve to the lower end of the cooling coil, an outlet nipple on the distributing chamber surrounding said upper end of the cooling coil, a water tube surrounding the cooling coil within the shell, the upper end of the water tube being connected to said nipple, the lower end of the water tube opening within the shell, and a cold water outlet in the top of the shell and located through said water distributing chamber.

4. A liquid cooler comprising a shell, a water distributing chamber mounted upon the top of the shell, means for supplying water to said distributing chamber, a cooling coil in the shell, the upper end of the coil being located through the distributing chamber, an evaporated refrigerant return line connected to said upper end of the coil, a control valve, a refrigerant supply line connected to said valve, a refrigerant distributor tube connecting the valve to the lower end of the cooling coil, an outlet nipple on the distributing chamber surrounding said upper end of the cooling coil, an elastic water tube surrounding the cooling coil within the shell, the upper end of the water tube being connected to said nipple, the lower end of the water tube opening within the shell, and a cold water outlet in the top of the shell and located through said water distributing chamber.

5. A liquid cooler comprising a shell, a water distributing chamber mounted upon one side of the shell, means for supplying water to said distributing chamber, a plurality of cooling coils in the shell, one end of each coil being located through the water distributing chamber, a header connected to said one end of each coil, an evaporated refrigerant return line connected to said header, outlet nipples on the water distributing chamber surrounding said ends of the cooling coils, water tubes surrounding the cooling coils within the shell and connected at one end to said outlet nipples, the other ends of the water tubes opening into the shell, a refrigerant distributor, means for supplying refrigerant to the refrigerant distributor, refrigerant distributor tubes connecting said refrigerant distributor to the other ends of the cooling coils, and a cold water outlet in the shell.

6. A liquid cooler comprising a shell, a water distributing chamber mounted upon one side of the shell, means for supplying water to said distributing chamber, a plurality of cooling coils in the shell, one end of each coil being located through the water distributing chamber, a header connected to said one end of each coil, an evaporated refrigerant return line connected to said header, outlet nipples on the water distributing chamber surrounding said ends of the cooling coils, elastic water tubes surrounding the cooling coils within the shell and connected at one end to said outlet nipples, the other ends of the water tubes opening into the shell, a refrigerant distributor, means for supplying refrigerant to the refrigerant distributor, refrigerant distributor tubes connecting said refrigerant distributor to the other ends of the cooling coils, and a cold water outlet in the shell.
